UNITED STATES PATENT OFFICE

SAMUEL F. NEWMAN, OF WAYNESBORO, PENNSYLVANIA, ASSIGNOR TO LANDIS MACHINE COMPANY, OF WAYNESBORO, PENNSYLVANIA, A CORPORATION

CHASER AND MEANS FOR HOLDING THE SAME

Application filed March 12, 1927. Serial No. 174,850.

My said invention relates to chasers and means for clamping the same, used in cutter heads for cutting threads on pipes, tubes, etc., said chasers being of the tangential type.

5 When cutting long tapered threads such as are commonly used on pipes and tubes, it is necessary to use chasers of different widths as the length of the threads is determined by the width of the chaser. Heretofore in order to use different width chasers it was necessary to completely change the chaser holding mechanism. In cutting threads on tubes and pipes there is a large variety of lengths combined with changes in 10 pitch and taper and it is desirable to use chasers so that the proper combination of pitch, taper and length of threads is secured without excessive width chasers or chaser holders being used, or without the substitution of new holders.

It is an object of this invention to provide chasers and chaser holding mechanism so that different width chasers can be secured in the same holding or clamping device. 15 Another object of my invention is to secure positive adjustment and backing-up means to the chaser so as to secure ease and accuracy of adjustment of the chaser laterally in the holder and to provide abutting means to 20 properly take up the resultant forces due to thread cutting. Other objects of my invention will become apparent as the description proceeds.

Referring to the accompanying drawings 25 which are made a part hereof and on which similar reference characters indicate similar parts,

Figure 1 is a plan view of the chaser mounted in its holder,

30 Figure 2, a side elevation,

Figure 3, a front elevation of the same,

Figure 4, a side elevation corresponding to Fig. 2 but using wider chasers,

Figure 5, a side elevation using a still 35 wider chaser.

Figure 6, a plan elevation of Figs. 4 and 5,

Figures 7, 8, 9 and 10, are views of different width chasers, and

Figures 11 and 12 are views of the clamp 40 which holds and abuts the chaser.

In Figs. 1 to 6 of the drawings reference character 10 indicates a slide or holder of any conventional design on which may be mounted a chaser as 12, 13 or 14. As shown in Fig. 2, the holder member 10 has an inclined shoulder 11 for receiving the beveled edge 15 of the chaser 12. A clamping member 16 has parallel depending edges 17 and 20 cut at an angle to fit corresponding grooves 18 and 21 in the holder 10 and the chaser 12 respectively. As shown in Fig. 2, the inner edge 17 of the clamp rests upon the inclined shoulder of the groove 18 in the holder 10. The edge 20 is cut at an angle opposite to that of the edge 17 and engages a beveled notch 21 in the chaser 12. It will be apparent from the showing in Fig. 2 that as the clamp 16 is tightened to the holder 10 the beveled edges 17 and 20 riding upon the inclined surfaces 18 and 21 will force the chaser 12 tightly against the seat 11 and at the same time will hold it securely against the face of the block somewhat in the nature of a dovetail joint. The chasers are adjusted longitudinally of the holders by screws 22 seated in non-threaded holes 23 of the holder 10 and operating on worm threads 24 of the chasers.

As shown in Fig. 11 the clamping member 25 has a projecting ear 26, the said ear having a threaded opening 27 for receiving abutting screws 28 which screws abut against the chaser.

Figs. 7, 8 and 9 show different width chasers which may be used in the same holder 30 and clamp. Fig. 7 has a beveled base 15 and a cut-away back at 21 and a cut-away portion at 34. Fig. 8 has a beveled base 15', a cut-away back at 21' and a portion of the opposite side from the beveled base cut-away as at 29. Fig. 9 has a beveled portion at 30, a back cut-away at 21'', a projecting portion 31 adjacent to the beveled base and a portion cut-away at 32 opposite the beveled base and projecting portion 31. The chasers shown in 35 Figs. 7, 8 and 9 all have worm threads hobbed on the back at 24, 24' and 24'' respectively.

Fig. 10 is a face view of Figs. 7, 8 and 9 showing a cut-away corner portion 32 to provide an abutting edge. This corner is design-

nated as 29 and 32 in Figs. 7 and 8 respectively.

The purpose of the cut-away portions 34, 29, and 32 on chasers 12, 13 and 14 is to provide an abutting edge or corner on the chaser against which an extending ear 26 on the chaser clamp 25 abuts. The abutment 26 on the clamp has a screw 28, as shown in Fig. 6, which receives the thrust of the chaser 10 against the clamp. Without the ear 26 on the clamp to receive the end thrust of the chaser during cutting operations the whole thrust on the chaser would have to be against the abutting screw 22. With very large chasers, 15 therefore, it is necessary to provide abutting means at the end of the chaser and near the top of the chaser to assist in receiving the end thrust. Unless the chasers were cut-off as shown in Figs. 8 and 9 the ear 26 would 20 have to rest against the outer end of the chaser.

In using my invention the chasers may be mounted upon the holder 10 as shown in Fig. 4 or 5 and the clamping device accurately 25 positioned by means of dowel pin 33 and clamped to the holder 10 by means of bolts or screws 19. The chaser is abutted and held in its adjusted position through the medium of screws 28 and the chaser members are 30 adjusted longitudinally of the holders by means of screws 22.

From an inspection of the chasers shown in Figs. 7, 8 and 9 and their position in Figs. 4 and 5, it will be apparent that chasers of 35 various widths may be clamped to the holder 10 by my clamping device without changing any of the parts.

It will be obvious to those skilled in the art that various changes may be made in my 40 device without departing from the spirit of the invention, and I, therefore, do not limit myself to what is shown in the drawings and described in the specification, but only as set forth in the appended claims.

45 Having thus fully described my said invention, what I claim as new and desire to secure by Letters Patent, is:

1. A chaser or cutter having a longitudinally grooved face for forming screw threads 50 and a beveled side adjacent to the grooved face, a portion of its back being cut-away to form a clamping member in conjunction with the beveled side, with worm threads cut on its back adjacent to the beveled side, and with 55 the side opposite to the beveled side cut-away to form an abutment, substantially as set forth.

2. A chaser or cutter having a longitudinally grooved face for forming screw threads 60 with portions of its back cut-away to leave an upper extended portion and to form oppositely inclined ribs, worm threads cut upon its back, and having a part of the upper extended portion cut-away to form an 65 abutment, substantially as set forth.

3. A chaser or cutter formed with a longitudinally grooved face for forming screw threads, with a portion of the back cut-away to provide a shoulder adapted to be received in a recess on a holder, a corner portion of the chaser being cut-away to provide for the reception of an abutting member whereby the chaser may be held securely in position during cutting operations, substantially as set forth.

4. A chaser holding device adapted to hold chasers of different widths comprising a holding block recessed to receive the chaser, and clamping means for securing the chaser in the recess, the said clamping means being provided with a projecting ear adapted to receive the cutting thrust of the chasers, substantially as set forth.

5. A chaser clamping device comprising a base member having an elongated beveled portion adapted to receive a corresponding beveled portion of a chaser, a clamping member secured to the said base and having a depending edge co-operating with the beveled portion on the base to hold the chaser in position, the said clamping member having an ear and adjustable abutting means therein, whereby chasers or cutters of various sizes may be used without changing the clamp, substantially as set forth.

6. A chaser or cutter having a longitudinally grooved face for forming screw threads, with upper and lower portions of its back cut away to form oppositely inclined ribs having upper and lower portions extending beyond the ribs, worm threads cut upon the back and having a part of the upper extended portion cut away to form an abutting surface for an abutting element on the clamp, substantially as set forth.

In witness whereof, I have hereunto set my hand at Waynesboro, Pennsylvania this 9th day of March, nineteen hundred and twenty-seven.

SAMUEL F. NEWMAN.
